UNITED STATES PATENT OFFICE.

CHARLES B. HASKELL, OF SOUTH PORTLAND, MAINE.

COLLAPSIBLE TUBE AND THE LIKE.

Application filed January 4, 1923. Serial No. 610,688.

To all whom it may concern:

Be it known that I, CHARLES B. HASKELL, a citizen of the United States, residing at South Portland, in the county of Cumberland and State of Maine, have invented certain new and useful Improvements in Collapsible Tubes and the like, of which the following is a specification.

My invention relates particularly to the so-called collapsible tubes designed to hold toothpaste, shaving cream, paint, and other substances of a like creamy consistency. These collapsible tubes are provided with screw-threaded nozzles and the nozzle is closed by a screw cap. To extract any of the contents of the tube the cap must be entirely removed from the nozzle and the contents of the tube squeezed out. The cap is thus liable to be lost and this fact often becomes annoying to the user.

In order to avoid removing the cap it has been proposed to so construct it that it cannot be entirely unscrewed from the nozzle and various openings have been formed in the cap and the nozzle through which the contents of the tube may be forced when occasion requires that it shall be used but these openings are usually of small diameter and are liable to get stopped up when the creamy material dries and hardens.

The object of my invention is to form an opening through the screw cap which will permit the escape of the material of the tube and permit any excess to be removed from the vicinity of the opening by wiping, scraping or otherwise clearing the vicinity of the opening so as to prevent any excess material drying and clogging it up.

My invention in its preferable form consists in chamfering off one corner or edge of the screw cap thereby forming an opening which will connect with the inside of the nozzle when the cap is partially unscrewed while at the same time making a tight joint when the cap is screwed to its closed position.

With an opening thus formed, the entire chamfered surface may be wiped or scraped off of any excess material or the thread of the nozzle will act to secure this result as the cap is turned.

While I have referred to my invention as applicable to collapsible tubes, it may also be applied to any form of container such

as a bottle, using a screw-threaded nozzle and a screw cap and designed for containing freely flowing liquids.

In the accompanying drawing, I have illustrated a variety of forms in which my invention can be constructed.

Referring to the drawing,—

Fig. 1 is a plan of the top of a collapsible tube with the screw cap in place and in open position,

Fig. 2 is the same with the cap removed,

Fig. 3 is a section on the line 3—3 of Fig. 1,

Fig. 4 is a front elevation of the same,

Fig. 5 is a side elevation taken at right angles to the position shown in Fig. 4.

Fig. 6 is a section on the line 3—3 showing the cap closed, and

Fig. 7 is a vertical longitudinal section through a modified form of the device having the cap set at an angle with the body of the tube,

Referring to the form shown in Figs. 1 to 6, 1 indicates the collapsible tube; 2 is the screw-threaded nozzle and 3 is the cap.

The opening is formed by chamfering the corner of the cap by a cut extending in a plane surface from the upper surface diagonally through the cap and removing a generally triangular section from the upper corner of the cap as shown at 4.

This chamfering cut may be removed from the cap alone or it may include a portion of the nozzle. In Figs. 3 and 6, a portion of the nozzle is removed, shown at 4', so that the plane or cut surface when the cap is screwed down to its closed position will include a portion of the cap, a portion 4 of the nozzle and a portion of the disk or gasket 5.

For the purpose of holding the cap in position, the diameter of the nozzle below the screw-threaded portion is slightly smaller than the screw-threaded portion as shown at 6 and the lower end of the cap is turned slightly inward as shown at 7.

There is thus formed at the lower end of the screw-threaded portion of the nozzle a shoulder 8 against which the inturned portion 7 of the cap will strike as the cap moves upward.

The cap is thus prevented from being entirely removed from the nozzle.

As will be seen in Fig. 3, when the cap is unscrewed either wholly or partially, an

opening 10 is formed through the chamfered portion between the upper end of the nozzle and the lower surface of the cap.

There is thus formed an elongated opening of greater or less thickness or width through which a ribbon-shaped portion of the material will be forced as the tube is squeezed.

Any surplus material which may adhere around the opening may be wiped off from the chamfered surface or when the cap is unscrewed, the screw thread of the cap will have a tendency to clear the opening and remove any dried material which may adhere around it.

When the cap is screwed tightly in place a tight joint 11 is formed which effectually prevents the admission of air and the drying up of the contents of the tube.

In Fig. 7, I show modification in which

the nozzle and cap are set at an angle with the body of the tube so that the chamfered surface 4 comes in line substantially with the center of the tube and when the tube is held upright the discharge opening for its contents will be directly beneath and in line with the center.

I claim:—

In a collapsible tube for toothpaste and the like embodying a screw-threaded nozzle, 30 an opening in the top of the nozzle, a screw cap therefor, said cap being chamfered off at the juncture of the end and side wall to form an opening in the cap, said opening being normally out of alignment with the 35 opening in the nozzle whereby the partial unscrewing of the cap will form a direct opening into the interior.

CHARLES B. HASKELL.
